(57) **CLAIM**

The ornamental design for a bottle, as shown and described.

DESCRIPTION

FIG. 1 is a top front perspective view of a bottle according to a first embodiment of our new design;

FIG. 2 is bottom rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top front perspective view of a bottle according to a second embodiment of our new design;

FIG. 10 is bottom rear perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof;

FIG. 16 is a bottom plan view thereof;

FIG. 17 is a top front perspective view of a bottle according to a third embodiment of our new design;

FIG. 18 is bottom rear perspective view thereof;

FIG. 19 is a front elevation view thereof;

FIG. 20 is a rear elevation view thereof;

FIG. 21 is a right side elevation view thereof;

FIG. 22 is a left side elevation view thereof;

FIG. 23 is a top plan view thereof;

FIG. 24 is a bottom plan view thereof;

(Continued)

FIG. 25 is a top front perspective view of a bottle according to a fourth embodiment of our new design; FIG. 26 is bottom rear perspective view thereof; FIG. 27 is a front elevation view thereof; FIG. 28 is a rear elevation view thereof; FIG. 29 is a right side elevation view thereof; FIG. 30 is a left side elevation view thereof; FIG. 31 is a top plan view thereof; and, FIG. 32 is a bottom plan view thereof.

The bottle is shown with a symbolic break in its length. The appearance of any portion of the article between the dash-dot-dot-dash break lines forms no part of the claimed design. The broken lines indicate portions of the bottom that form no part of the claim.

1 Claim, 28 Drawing Sheets
